PROCESS FOR SWEETENING HYDROCARBON OILS

Lovell V. Chaney and Albert E. Buell, Bartlesville, Okla., assignors to Phillips Petroleum Company, a corporation of Delaware

Application July 25, 1936, Serial No. 92,630

7 Claims. (Cl. 196—29)

This invention relates to the refining of hydrocarbon fluids. More particularly, it relates to improvements in the sweetening of "sour" petroleum hydrocarbon products by means of a moist 5 solid reagent comprising copper chloride adsorbed on carriers.

The improved method of refining petroleum hydrocarbon products herein set forth is of special value and application in the treatment of 10 light petroleum distillates such as natural gasoline, refinery straight run and cracked gasolines, kerosenes, petroleum solvent naphthas, liquefied petroleum gases; and the like. Such unrefined petroleum products contain mercaptans which 15 give the products undesirable odors and render them corrosive and unstable. Petroleum hydrocarbon products containing mercaptans are commonly termed "sour". Conversion of these mercaptans partially or entirely to disulfides, or 20 completely removing them, is usually termed sweetening. Customarily, these "sour" compounds are altered, or removed, by chemical treatment of the "sour" hydrocarbon fluid with alkali plumbite and sulfur. In some instances, 25 particularly with natural gasoline, sweetening is accomplished with alkaline hypochlorite solutions but, like the alkali plumbite method, this method has proved to be not only uneconomical and cumbersome but also has been found to 30 introduce undesirable constituents into the products being sweetened, such constituents in many instances of high mercaptan content products being detrimental to the petroleum products treated as those present originally. Still other 35 methods have been suggested for the removal or conversion of mercaptans but in nearly every instance these methods involve numerous treating steps, requiring close control, so that the increase 40 in operating costs renders them uneconomical.

The object of this invention is to provide an economical and easily operated method for refining sour petroleum hydrocarbon oils.

A further and more specific object is to provide 45 improvements in the method of sweetening sour petroleum hydrocarbon oils by means of a moist refining agent consisting of carrying agents impregnated with cupric chloride, said refining agent being retained in a constantly active state 50 by air dissolved in the sour hydrocarbon oils.

In co-pending application Serial No. 725,405, 55 a novel method of sweetening petroleum hydrocarbon products was described, whereby sweetening is accomplished by passing a sour petro-

leum product through a bed of moist treating agent comprising cupric chloride carried on fuller's earth, or other porous and adsorbent carrier, and the treating agent maintained in an active or sweetening state by means of air added to the petroleum hydrocarbon oil being sweetened.

The petroleum products to be sweetened, and to which air or other gas containing free oxygen has been added, are passed through beds of this 10 treating agent, the petroleum products flowing either upward or downward through the beds. On emerging from the treating agent bed, the gasoline or other petroleum hydrocarbon fluid, is 15 sweet to the well known "doctor" test, has an excellent odor and does not contain any of the undesirable constituents, many of which are unstable to light or heat, usually introduced into the sweetened product by the aforementioned customary sweetening methods.

As disclosed further in co-pending application 20 Serial No. 725,405, the principal chemical reactions in sweetening sour petroleum hydrocarbon oils with cupric chloride carried on an adsorbent material are believed to be as shown in 25 the following equations:

In the first step of the reaction, one-half of the mercaptan is converted to the alkyl disulfide and the rest is left as cuprous mercaptide. The latter then reacts (as shown in Equation 2) with 35 additional cupric chloride to give alkyl disulfide and cuprous chloride. On combining the two equations into one, the ultimate reaction is:

Since cuprous chloride and hydrochloric acid are formed in the reaction at the expense of the cupric chloride, the reagent, when treating petroleum oil without the addition of air, will gradually lose its activity, and finally become spent, as the amount of mercaptan sulfur in the oil passed through the reagent becomes more nearly equivalent to the cupric chloride used on the reagent. When the petroleum oil contains only a very small quantity of mercaptan sulfur the life of the reagent is comparatively long, but when the mercaptan content is high the life of the reagent is quite short.

Spending of the reagent is prevented and its activity maintained over long periods by dissolving air in the petroleum oil previous to its passage through the reagent bed. In this manner 5 the cuprous chloride and hydrochloric acid, formed as shown above in the sweetening step, react with the oxygen in the air to give cupric chloride and water.

The treating agent contains a substantial quantity of water and the hydrogen chloride formed as shown in Equation 1 is dissolved in the 15 water or, rather, in the solution of the copper salt. The cuprous chloride likewise remains in solution at the same point in the bed. The oxygen needed to convert the cuprous chloride and hydrochloric acid back to cupric chloride is furnished by the oxygen in solution in the oil and the reagent is immediately and continuously regenerated. If insufficient water is present, the 20 hydrogen chloride passes off as a gas dissolved in the oil and the cuprous chloride is precipitated in the solid form. When the hydrogen chloride is carried away from the cuprous chloride the 25 regeneration does not take place and the reagent therefore soon becomes spent. In this petroleum oil treating process sufficient moisture is maintained in the treating agent such that it has a 30 water content substantially greater than that of an adsorbent mixture of cupric chloride hydrate crystals and substantially dry adsorbent material. Continuous regeneration of the cupric chloride is obtained and the treating agent remains in a 35 highly active state over long periods of time during which many equivalents of mercaptan sulfur are sweetened by one equivalent of cupric chloride.

40 Spending of the treating agent, due to insufficient water, has been observed in the commercial application of this process where the petroleum oil was exceptionally free from dissolved water and it was, therefore, necessary to 45 add water to the oil being processed or to the solid treating agent.

In the commercial practice of the process as described in said co-pending application the volume of petroleum oil which can be treated per 50 volume of the cupric chloride sweetening agent varies widely in different instances where the oil and sweetening agent are identical. This variation is due to variations in the rate at which the 55 petroleum oil is passed through the sweetening agent bed. For example, when treating a very sour petroleum oil a greater volume can be treated per volume of sweetening agent when the oil is treated at relatively low rates, such as a linear 60 velocity of 0.4 ft. per minute through the sweetening agent bed, than at higher rates such as 4.0 ft. per minute. This is due to less complete regeneration of the sweetening agent at the higher rates, the regeneration apparently not being as 65 rapid as the sweetening.

65 On the other hand, we have found that when the sweetening agent failed to sweeten after having been used consistently at very low rates, an average sample of the sweetening material has practically the same potential sweetening power 70 as it had originally, indicating that small channels had formed in the bed of sweetening material and set up a condition equivalent to sweetening at high rates through the local areas in the bed where channelling had occurred.

75 We have found that this failure in sweetening

due to channelling can be prevented by passing the oil at a relatively high rate upward through the bed of sweetening agent for periods of short duration at relatively frequent intervals. This serves to lift the reagent bed slightly and to disturb the granules thereof sufficiently to break up incipient channels in the bed. 5

Where the treating agent has failed to sweeten the petroleum oil, due to the formation of these channels, we have obtained a large increase in 10 volume of oil sweetened, per volume of treating agent, by passing the oil up through the treating agent bed at rates between 0.7 and 2.5 ft. per minute. When the flow rate of the oil up through the bed is less than about 0.7 ft. per minute, the 15 velocity is not high enough to disturb the granules of treating agent sufficiently to break up the channels, and rates in excess of about 2.5 ft. per minute cause so much lifting that particles of the treating agent are carried out of the container by the oil stream. We prefer to carry out 20 this step in the process by passing the petroleum oil up through the treating agent bed at rates between 1.0 and 1.8 ft. per minute, although the preferred rate in individual cases is influenced 25 somewhat by the size and shape of the treating agent granules, by the depth of the treating agent bed and by the density of the petroleum oil.

We prefer to treat at rates such that the linear 30 velocity of the petroleum oil through the sweetening agent is less than 0.5 ft. per minute where the oil contains only a moderate concentration of mercaptans and less than 0.2 ft. per minute where the oil is very sour, or contains a relatively high concentration of mercaptans. 35

As an example of the utility of this step in the refining of petroleum hydrocarbon products with a refining agent consisting of cupric chloride carried on fuller's earth, a treating plant processing a very sour (0.05 per cent, by weight, mercaptan 40 sulfur) West Texas natural gasoline at an average rate of 14,000 gallons per day through a bed of this refining agent 4 ft. deep and 4 ft. in diameter consistently sweetened approximately 200,000 gallons of gasoline after each filling of the treating tank with cupric chloride refining agent before failing to completely sweeten the gasoline. In this normal treating the gasoline was passed through the refining agent bed at rates approximating a linear velocity of 0.13 ft. per minute. A 50 pump was then installed and gasline passed up through the refining agent bed for 20 to 30 minutes every 3 or 4 days, or after approximately every 50,000 gallons of gasoline had been sweetened, at a rate of 150 gallons per minute, or at 55 approximately 1.6 ft. per minute. Other than this periodical short cessation of normal sweetening operation, the cupric chloride treater operated continuously for over 8 months and sweetened over 3,500,000 gallons of this very sour 60 natural gasoline without once opening up the treater or otherwise disturbing the refining agent bed. In normal sweetening operation the gasoline flows continuously from the fractionator kettle through an alkaline sodium polysulfide 65 treater, to remove elementary sulfur, and down through this cupric chloride refining agent bed.

In the drawings:

Fig. 1 illustrates, diagrammatically, a system for carrying out the present invention; 70

Fig. 2 is a view, partially in section, of an apparatus for introducing air or oxygen into the hydrocarbon stream;

Fig. 3 is a sectional view of a treater.

It is to be understood that the specific system 75

and apparatus shown in the accompanying drawings are for the purpose of illustration only, and indicate one manner in which applicants' invention can be carried out, and that other systems 5 and apparatus suitable for carrying out the invention as described and claimed may be substituted.

Fig. 1 illustrates the operation of our improved method of sweetening petroleum hydrocarbon 10 oils with cupric chloride solution on a solid carrier. In normal sweetening operation, sour petroleum oil enters the oil and air contacting chamber 3 through pipe 1. A controlled amount of air enters contacting chamber 3 through pressure reducing regulator 4, valve 5 and check valve 15 8. Automatic proportioning of air into the hydrocarbon oil is accomplished by proportional control 9 working in conjunction with diaphragm valve 7 motivation for which is furnished by differentials across hydrocarbon oil orifice 2 and 20 air orifice 6, co-acting through an air block or pilot valve actuated by an external source of air at constant moderate pressure, so that every change in the flow rate of hydrocarbon oil causes 25 a proportional change in air rate. The desired proportion of air to petroleum hydrocarbon oil is established by drilling the orifices in the orifice plates in the air and petroleum oil lines to the proper sizes for the desired proportions.

30 Sour petroleum oil containing the air passes then from contacting chamber 3 through line 10, through valves 11 and 12 and through line 13 into the top of tank 14 in which is contained a bed of moist sweetening agent consisting of cupric 35 chloridesolution on a carrier material. Petroleum oil passes down through the bed of refining agent and emerges, sweetened, from treating tank 14 through line 15, valve 16 and through line 17 to sweet oil storage. Valves 18, 19, 20, 21, 23 and 40 24 are closed.

After a predetermined volume of petroleum oil has been sweetened through treating tank 14, for example, valve 12 is closed and valves 18, 32, 34, 36 and 19 are opened so that oil through line 10, 45 line 31, tank 33, centrifugal pump 35 and line 38 will completely fill tank 14 when air and vapors are vented from tank 14 by opening valve 30. When tank 14 is liquid full, valves 11 and 30 are closed, valve 12 is opened and pump 35 is started. 50 Circulation of oil is then in the reverse direction to that in normal sweetening, oil being drawn from the top of tank 14 through lines 13 and 37 into surge tank 33. Pump 35, taking suction from the bottom of surge tank 33, discharges oil 55 through line 38 and line 15 into the bottom of treating tank 14 below the sweetening agent bed. Flow rate of oil up through the tank is determined by orifice 26 and manometer, or recording flowmeter, 27 and the flow rate regulated by valve 36 so that the velocity of oil up through the treating 60 tank is approximately 1.5 ft. per minute. Orifices 26 and 28 are square-edged so that the flow of oil in either direction can be measured with them in conjunction with a manometer or 65 with a specially arranged recording flowmeter.

After passing petroleum oil at the prescribed rate up through the cupric chloride refining agent in treating tank 14 for 20 to 30 minutes, pump 35 is stopped, valves 18 and 19 are closed and 70 normal sweetening resumed by opening valves 11 and 16. During the short period of reverse flow in treating tank 14, sour petroleum oil is sweetened by passage through cupric chloride refining agent in treating tank 25. Sizes of treating tanks 75 and quantities of sweetening agent are used such

that the total normal petroleum oil sweetening requirement can be sweetened in the remaining treating tanks while any one is out of service for the short period of reverse flow.

Flow of air into the petroleum oil is also controlled and recorded by means of a needle valve, 5 not shown, in the air line to the oil and air contacting chamber 3, Fig. 1, orifice 6 and a recording flowmeter or a manometer, also not shown in Fig. 1.

Automatically proportioning the air into the gasoline is essential where the quantity of mercaptans in the gasoline is of such magnitude that the air required to maintain the cupric chloride treating agent in a continuously regenerated state 10 is approaching the solubility of air in the hydrocarbon oil being processed. Without an automatic proportioner, the tendency in this critical range would be either to add too much air to the oil, and raise the vapor pressure of the oil, 15 or to add too little, with the possible chance of permitting the treating agent to become spent. Automatically proportioning the air into the hydrocarbon oil is preferred where the mercaptan content of the oil is of the order of 0.04 per 20 cent by weight. Where the mercaptan content is around 0.002 per cent, air is satisfactorily added to the oil by manual control.

Sometimes sweetening is also carried out by admitting the sour petroleum oil into the bottom 30 of treating tank 14, Fig. 1, and passing the oil up through the sweetening agent bed at a relatively low rate, removing the sweetened oil from the top of the tank. Fig. 1 is not complicated with the extra lines and valves to show treating in 35 this manner. After normally treating up-flow at a relatively low rate for a predetermined time, upward flow of petroleum oil is increased periodically to the desired high rate by means of a pump, or other means for obtaining this high 40 rate, for a relatively short time, after which normal treating is resumed.

Where the sour hydrocarbon oil can be supplied to the treating agent, in this reverse flow step, in sufficient quantity to maintain the required upward flow rate for the desired length of time, 45 the oil is passed up through the cupric chloride treating agent bed but once and then passed on to sweet storage, rather than recycled, for even at the higher rates required for the slight disturbance of the treating agent bed the oil is completely sweetened. In this manner of maintaining the high flow rate up through the treating agent bed, air is added to the gasoline in the required proportion to maintain the treating agent 50 in a regenerated state, whereas in the recycling method no regenerating air is necessary.

In sweetening through two or more treaters in parallel, valves 20, 22 and 23, controlling the flow of petroleum oil into and out of treating tank 60 25, are open as are correspondingly placed valves on other treating tanks if more are in the system. Square-edged orifices 26 and 28, with corresponding manometers or flowmeters 27 and 29, are conveniently placed in the lines into the 65 top of the treating tanks in order to determine that the desired amount of petroleum oil is passing through each of the treating tanks arranged in parallel and to regulate the periodical relatively high rate of upward flow of oil through 70 the sweetening agent for the prevention of channelling.

Fig. 2 illustrates in detail a typical device for mixing air, or other oxygen-containing gas, with the petroleum oil to be sweetened with the cupric 75

chloride treating agent. Petroleum oil enters through conduit 1 into chamber 3 where it is intimately commingled with air entering the chamber through conduit 40 and porous plate 41, the porous plate serving to subdivide the air stream many times to greatly increase the contact surface between air and petroleum oil. Porous plate 41 is composed of Alundum, or other similar material, and is maintained in a swedge nipple with babbitt 42. The petroleum oil and air mixture leaves chamber 3 through conduit 10.

Fig. 3 shows the construction of a typical treating tank containing cupric chloride sweetening agent. During sweetening operation sour petroleum oil, partially saturated with air, enters tank 14 through conduit 13, impinging against baffle 43 to prevent disruption of the granular treating agent bed by the flow of oil. The sour petroleum oil is sweetened in passing through sweetening agent 44, and the sweetened oil passes through perforated wooden plates 45, hair-felt 46 and leaves tank 14 through conduit 15. Sweetening agent 44 is supported by two perforated wooden plates 45, consisting of perforated boards arranged to form a floor, the two plates being held apart by spaced boards 47, and the whole supported by steel beams 48 resting on an angle iron ring 49. Hair-felt 46, or the like, packed tightly between the perforated plates prevents the granular sweetening agent from passing through the plate perforations.

During the step of periodically passing petroleum oil up through the sweetening agent bed at a relatively high rate to break up incipient channels in the bed, oil enters through conduit 15, Fig. 3, impinging upon baffle plate 50, passes up through sweetening agent 44 and leaves treating tank 14 through conduit 13. Oil partially saturated with air, is also passed up through the sweetening agent bed at lower rates during the normal sweetening operation.

Manholes 51, Fig. 3, are provided for admitting sweetening agent to treating tank 14 through the top and for removing it therefrom at the side. 45 Drain 52 is provided for completely emptying tank 14 of liquid.

Having described our invention what we claim and desire to secure by Letters Patent is:

1. A process for sweetening mercaptan-bearing petroleum oil, comprising impregnating a solid adsorbent carrier material with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, admixing a free oxygen-containing gas with said mercaptan-bearing petroleum oil, contacting said oil and free oxygen-containing gas with said impregnated adsorbent material, thereby converting the mercaptans in said oil to disulfides and simultaneously maintaining the sweetening agent active, and collecting the sweetened petroleum oil, discontinuing contacting said petroleum oil and admixture of free oxygen-containing gas with said impregnated adsorbent material, subsequently passing said petroleum oil up through said impregnated adsorbent material at a relatively high velocity for a relatively short duration of time, discontinuing said relatively high velocity of upward passage of petroleum oil through said impregnated adsorbent material and resuming contacting of said admixture of petroleum oil and free

oxygen-containing gas with said impregnated adsorbent material.

2. A cyclic process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing a free oxygen-containing gas with said mercaptan-bearing petroleum oil, contacting said oil and free oxygen-containing gas with said impregnated adsorbent material, thereby converting the mercaptans in said oil to disulfides and simultaneously maintaining said sweetening agent active, and continuously collecting the sweetened petroleum oil, discontinuing contacting said mercaptan-bearing petroleum oil and admixture of free oxygen-containing gas with said impregnated adsorbent material, subsequently passing a petroleum oil up through said impregnated adsorbent material at a relatively high velocity for a relatively short duration of time, discontinuing said relatively high velocity of upward passage of petroleum oil through said impregnated adsorbent material, and repeating the process.

3. A process for sweetening mercaptan-bearing petroleum oil, comprising impregnating fuller's earth with a solution of copper sulfate and a soluble alkaline chloride, maintaining the water content of said impregnated fuller's earth substantially above that of a mixture of cupric chloride hydrate crystals and substantially dry fuller's earth, mixing air with said petroleum oil, filtering said petroleum oil and air downward through said impregnated fuller's earth at a rate in the range of 0.05 to 0.4 ft. per minute, whereby the mercaptans in said oil are converted to disulfides, and collecting the sweetened oil, discontinuing contacting of said admixture of petroleum oil and air with said impregnated fuller's earth, passing said petroleum oil up through said impregnated fuller's earth at a rate in the range of 0.7 to 2.5 ft. per minute for approximately one-half hour, discontinuing said upward passage of petroleum oil and resuming downward passage of said admixture of oil and air through said impregnated fuller's earth, and collecting the sweetened oil.

4. A cyclic process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, contacting said oil and air with said impregnated adsorbent material, thereby converting the mercaptans in said oil to disulfides and simultaneously maintaining said sweetening agent active, and collecting the sweetened petroleum oil, discontinuing contacting said petroleum oil and admixture of air with said impregnated adsorbent material, subsequently passing said petroleum oil up through said impregnated adsorbent material at a relatively high velocity for a relatively short

duration of time, discontinuing said relatively high velocity of upward passage of petroleum oil through said impregnated adsorbent material, and repeating the process.

5. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.
10. In a process for sweetening mercaptan-bearing petroleum oil with a solution of cupric chloride, maintaining the water content of said impregnated fuller's earth substantially above that of a mixture of cupric chloride hydrate crystals and substantially dry fuller's earth, adding
15. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.
20. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.
25. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.
30. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.
35. In a process for sweetening mercaptan-bearing petroleum oil with a solid adsorbent carrier material impregnated with a sweetening agent consisting of a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry solid adsorbent material, comprising admixing air with said mercaptan-bearing petroleum oil, passing said oil and air downward through said impregnated adsorbent material at a relatively low rate, thereby converting the mercaptans in said oil to disulfides and simultaneously maintaining said sweetening agent active, and continuously collecting the sweetened petroleum oil, the step of discontinuing the normal relatively low rate of passage of petroleum oil downward through the impregnated adsorbent material and passing said petroleum oil upward through the impregnated adsorbent material at a predetermined relatively high rate, thereby preventing the formation of channels in said impregnated adsorbent material.

air to said oil, filtering said oil and air downward through said impregnated fuller's earth at a rate less than approximately 0.4 ft. per minute, thereby converting the mercaptans to disulfides, and continuously collecting the sweetened oil, the step of periodically discontinuing filtering said oil and air through said impregnated fuller's earth, and subsequently passing a light petroleum oil up through said impregnated fuller's earth at a rate in the range of 0.7 to 2.5 ft. per minute for approximately one-half hour, thereby preventing permanent channelling of said impregnated fuller's earth.

7. In a process for sweetening mercaptan-bearing petroleum oil partially saturated with air, the steps which comprise passing said oil at a rate less than approximately 0.4 ft. per minute up through a sweetening agent consisting of a solid adsorbent material impregnated with a solution of a copper salt and a chloride adapted to react to form cupric chloride, said impregnated adsorbent material being maintained in a moist condition and having a water content substantially greater than that of an adsorbent mixture of cupric chloride hydrate crystals and substantially dry adsorbent material, periodically increasing the rate of passing said oil, partially saturated with air, up through said sweetening agent to a rate in the range of 0.7 to 2.5 ft. per minute for approximately one-half hour, decreasing said rate of upward passage of said oil through said sweetening agent to a rate less than approximately 0.4 ft. per minute, and repeating the steps.
